Hawley. Attorney.

UNITED STATES PATENT OFFICE.

JOHN F. HAWLEY, OF CHILlicothe, Missouri.

RAIL CHAIR AND CLAMP.

1,162,057.

Specification of Letters Patent. Patented Nov. 30, 1915.

Application filed June 5, 1915. Serial No. 32,352.

To all whom it may concern:

Be it known that I, JOHN F. HAWLEY, a citizen of the United States, residing at Chillicothe, in the county of Livingston and State of Missouri, have invented certain new and useful Improvements in Rail Chairs and Clamps, of which the following is a specification.

This invention contemplates an improved rail chair and clamp and relates more particularly to improvements in the structure disclosed in Patent No. 1,134,130 issued to me April 6, 1915.

The invention has as its primary object to provide a construction adapted to form a joint chair and to also provide, with but slight variation in structure, a chair adapted for general purposes.

The invention has as a further object to provide a chair having coacting elements, one of which is adjustable upon the other to securely engage a rail seated upon the chair.

A still further object of the invention is to provide a chair wherein the body portion thereof may be readily formed and which may be easily installed upon any conventional type of roadbed.

Other and incidental objects will appear as the description proceeds and in the drawings wherein I have illustrated the preferred embodiment of the invention and wherein similar reference characters designate corresponding parts throughout the several views, Figure 1 is a perspective view of my improved device showing the manner in which it is employed in use, Fig. 2 is a transverse sectional view more particularly illustrating the mounting and arrangement of the coacting elements of the chair, Fig. 3 is a perspective view showing the clamping member of the device detached, Fig. 4 is a top plan view illustrating a slight modification in the mounting of the chair from that shown in Fig. 1, Fig. 5 is a perspective view of a slight modification of the invention, Fig. 6 is a similar view showing a still further modification, Fig. 7 is a fragmentary perspective view of a modified form of clamping member, Fig. 8 is a sectional view showing the form of clamping member illustrated in Fig. 7 in position upon the body portion of the chair shown in Fig. 6, Fig. 9 is a perspective view showing the rail clamp of the present invention as used in connection with a metallic or composition tie substantially

similar in construction to the form of tie disclosed in my issued patent referred to, and Fig. 10 is a fragmentary longitudinal sectional view showing the manner in which the clamping member is arranged to coact with the tie to engage the rail.

In carrying out my invention, the body portion of the chair includes a substantially flat bed plate 10 upon one side of which is formed an upstanding longitudinally disposed abutment 11 in the nature of a fish plate adapted to fit against the outer side of the meeting ends of the rails conventionally shown at 12 and 13 respectively, in the manner shown in Figs. 1 and 2 of the drawings, it, of course, being understood that the rails are supported upon the bed plate.

The bed plate, in use, is arranged to seat upon adjacent ties 14 of the roadbed as shown in Fig. 1, and at suitable points, is provided with a plurality of openings adapted to receive spikes 15 for securing the body portion of the chair in position.

Formed on the outer longitudinal edge of the plate 10 and depending between the ties 14 is a laterally projecting arm or lug 16, while a similar lug 17 is struck from the opposite longitudinal edge of the plate and is arranged to depend between the ties in substantially parallel relation to the lug 16. The lugs or arms 16 and 17 are arranged in alinement and are provided with alined openings.

Associated with the body portion of the chair is a clamping member which includes a body portion 18 arranged to embrace the edges of the rails opposite the abutment 11 and which is provided, at one extremity with a vertically disposed head 19 adapted to seat against the webs of the rails upon the sides thereof opposite the abutment as particularly shown in Fig. 2 of the drawings. Arranged upon the head 19, at spaced points are laterally projecting studs 20 adapted to freely engage within suitable openings formed in the webs of the rails. Formed on the body portion 18 of the clamping member at its extremity opposite the head 19, is a laterally projecting shank 21 which is freely and slidably received within the alined openings formed in the lugs 16 and 17 and is screw threaded adjacent the outer extremity thereof to receive a nut 22 for adjustably connecting the clamping member with the body portion of the chair.

It will now be seen that the chair may be readily used in connection with any conventional type of roadbed and that in providing the clamping member of the device 5 the studs 20, the said device will form an efficient joint chair. However, as will also be readily understood, by eliminating the studs 20, the construction may be employed intermediate the ends of the rails to provide a chair therefor.

In Fig. 4 of the drawings, I have shown the chair of the present invention applied to one end of a conventional type of tie which has been formed with a longitudinally 15 extending recess 23 arranged to receive the lugs 16 and 17 of the body portion of the chair as well as the shank 21 and nut 22 of the clamping member. Thus, it will be seen that in use, it will be unnecessary for 20 the bed plate of the device to span adjacent ties as shown in Fig. 1 of the drawings, if found inexpedient, since the chair may be readily mounted upon a single tie by merely channeling the tie in the manner indicated.

In Fig. 5 of the drawings, I have shown a slight modification of the invention wherein the abutment 11 is formed separately from the bed plate 10 and is provided upon the outer longitudinal edge thereof, with a 30 depending lug or arm 24 adapted to fit over the lug 16 of the bed plate and provided with an opening adapted to align with the openings of the lugs 16 and 17 for receiving the shank of the clamping member. The 35 abutment 11 is also preferably provided with suitable openings 25 adapted to align with similar openings formed in the bed plate 10 for receiving the spikes, so that the abutment will be connected to the bed plate 40 by the said spikes. From the preceding description in connection with the preferred form of the invention, it is thought that the manner in which this modified structure will be employed in use, will be entirely 45 clear, and a further description thereof, will not, therefore, be given.

In Fig. 6, I have shown a further slight modification of the invention wherein the body portion of the chair is formed from 50 suitable resilient sheet metal bent upon itself to provide a bed plate 10 and an abutment 11. In this modification, the lug 26 is struck from the overlapping portion of the said element while the lug 27 is struck 55 from the opposite longitudinal edge of the plate, these lugs respectively corresponding to the lugs 16 and 17 of the preferred form of the invention. It will be seen that this modification provides a very simple construction and convenient manner of producing the body portion of the chair.

In Fig. 7 of the drawings, I have shown a slightly modified form of clamping member and in Fig. 8 have shown said clamping 65 member in connection with the body portion

of the chair illustrated in Fig. 6. This clamping member includes a body portion 28 adapted to embrace the adjacent edge of the bed plate 10 and which, at one extremity, is provided with a laterally extending shank 29 which is freely and slidably received within suitable aligned openings formed in the lugs 26 and 27 as in the preferred form of the invention. The shank 29 is screw threaded adjacent the outer extremity thereof and receives a nut 30 adjustably connecting the clamping member with the body of the chair. The body portion 28, at its extremity opposite the shank 29, is provided with a transversely disposed substantially 70 arcuate head 31 which curves inwardly toward the shank 29 and laterally toward the inner end of said shank as more particularly shown in Fig. 8 of the drawings. The head 31 upon its upper longitudinal edge is thickened to provide a reinforcing rib while the said head is longitudinally tapered toward its free end to form a yieldable bearing portion adapted to engage the base flange of a rail as shown in Fig. 8, with the upper thickened portion of the head confronting the web of the rail. In this figure, the rail has been conventionally shown at 32. Preferably, the clamping member of this modification of the invention will be formed of suitable resilient metal so that the head 31 of the said clamping member will be adapted to yieldably engage the rail 32 under the influence of the nut 30 tending to urge the said clamping member toward the abutment 11. 90 Moreover, the free end of the head, when in normal position, will be spaced from the shank 29 a distance less than the distance between the said shank and the upper face of the base flange of the rail so that when the clamping member is thus urged into position, the free end of the head thereof will tend to bear downwardly upon the said base flange for holding the rail firmly in position. Formed on the head 31 at spaced points, are 100 a plurality of laterally projecting studs 33 adapted to engage within suitable openings formed in the adjacent end of the rail 32 and the contiguous end of a meeting rail, to thus effectually connect the meeting ends of the rails together. Attention is now directed to the fact that in striking the lugs 17 in the preferred form of the invention from the bed plate 10 as well as in striking the lugs 27 of the modification shown in Fig. 6 110 from the bed plate, the bed plate is provided with a transversely extending notch or slot 34 adapted to slidably receive the body portion of the clamping member of the chair for supporting it laterally, or, in other words, to overcome any tendency of the body portion of the clamping member to shift laterally relative to the bed plate of the chair under the effect of strain upon the head of the clamping member such as would be 120 130

caused by a longitudinal thrust upon the rail supported by the chair. In thus supporting the body portion of the clamping member against lateral shifting movement 5 relative to the bed plate, strain which would otherwise be exerted principally upon the lugs 17 or 27 as the case may be, will be relieved. Furthermore, the said slot 34 will tend to guide the clamping member of the 10 chair when adjusted upon the body portion thereof and will tend to relieve undue strain upon the shank of the clamping member tending to bend the shank intermediate its length.

15 In Figs. 9 and 10 of the drawings, I have illustrated the preferred form of rail clamping member of the present invention in connection with a tie substantially similar in construction to the form of tie disclosed in 20 my issued patent referred to. In order that this adaptation of the invention may be entirely clear, it may be stated that the tie shown in this figure includes a body portion 35 which is hollowed out from the under side thereof, to provide side walls 36 which are formed with outwardly diverging inner faces and closing the under side of the tie is a removable bottom wall 36'. Formed integral with the body portion of the tie at the 30 ends thereof, are anchoring members 37.

The tie may be formed from metal, a composition, or any other suitable material and opening through the upper face thereof adjacent opposite ends of the tie are longitudinally extending slots 38. Formed on the upper face of the tie adjacent the outer extremities of the slots 38 respectively, are upstanding abutments 39 adapted to fit against the outer sides of the rails conventionally 40 shown at 40.

A pair of clamping members shown in Fig. 3 of the drawings may then be employed in holding the rails in position. The said clamping members are arranged with the body portions 18 thereof extending freely through the said slots and with the heads 19 fitting against the inner sides of the rails to coact with the abutments 39 in which position, the shanks 21 of the said 45 clamping members will project to extend freely through the anchoring members 27 and terminally receive nuts 41. As will now be clear, by tightening the nuts 41, the clamping members may be adjusted to securely engage the rails for holding them firmly seated upon the tie.

While I have indicated that the preferred form of clamping member illustrated in Fig. 3 is preferably employed in connection with 50 the tie shown in Figs. 9 and 10, as will be readily seen, the clamping member shown in detail in Fig. 7 may be readily substituted therefor, without the necessity of any structural change in the tie itself.

55 Having thus described my invention, what

I claim and desire to secure by Letters Patent is:—

1. A device of the character described including a bed plate formed with an abutment and having a slot opening through one edge thereof, a lug extending from the said plate and a clamping member received in said slot and adjustable upon the said lug to coact with the abutment in engaging a rail seated upon the bed plate. 70

2. A device of the character described including a bed plate provided with an abutment, the said bed plate having spaced arms depending therefrom and being provided with a slot arranged in alignment with said arms, and a clamping member adjustable upon said arms and slidably engaging within said slot, the said clamping member being movable to coact with the abutment in engaging a rail seating upon the bed plate. 80

3. A device of the character described including a bed plate having an abutment mounted thereon, spaced lugs carried by the bed plate, one of said lugs being struck from the plate to define a slot and a clamping member adjustable upon said lugs and freely engaging in said slot, the clamping member being movable toward the abutment to coact therewith in engaging a rail seating upon the bed plate. 85

4. A device of the character described including a bed plate having a depending lug formed on one edge thereof, an outstruck lug depending from the opposite edge of the plate an abutment carried by the bed plate, and a clamping member adjustable upon the bed plate and including a shank slidably mounted upon said lugs and a head adapted to coact with the abutment in engaging a rail seating upon the bed plate. 90

5. A device of the character described including a bed plate having spaced arms formed thereon, an abutment arranged to seat upon the bed plate and provided with an arm alining with said spaced arms and a clamping member adjustable upon said arms to coact with the abutment in engaging a rail seating upon the bed plate. 100

6. A device of the character described including a bed plate bent adjacent one extremity thereof to provide an abutment, spaced out-struck lugs carried by the bed plate, and a clamping member adjustable upon said lugs to coact with the abutment in engaging a rail seating upon the bed plate. 110

7. A device of the character described including a bed plate provided with an abutment and having spaced arms formed thereon, a clamping member carried by the bed plate and including a shank adjustably mounted upon said arms, and a longitudinally tapered arcuate head adapted to coact with the abutment to yieldably engage a rail seating upon the bed plate. 120

8. A device of the character described in- 125

cluding a bed plate provided with an abutment, and a clamping member carried by the bed plate and adapted to co-act with the abutment, said clamping member including 5 a head adapted to yieldably engage the base flange of a rail seating against said abutment.

9. A device of the character described including a bed plate provided with an abutment, and a clamping member associated 10 with the bed plate and adapted to coact with the abutment, the said clamping member including a head having its free end arranged to depend toward the base flange of 15 a rail seating against said abutment to engage with the said base flange.

10. A device of the character described including a bed plate provided with an abutment, and a clamping member associated 20 with the bed plate and adapted to coact with the abutment, the said clamping member including a longitudinally tapered head adapted to engage the web of a rail seating

against said abutment with the smaller end of the head engaging the base flange of the 25 rail.

11. A device of the character described including a bed plate provided with an abutment, and a clamping member associated therewith, the said clamping member including a head provided at one extremity with a transversely extending rib adapted to engage beneath the tread of a rail seating against said abutment with the head engaging 30 the base flange. 35

12. A device of the character described including an abutment, and a clamping member associated with the abutment, said clamping member including a substantially U-shaped body portion terminating at one extremity in a shank supporting the clamping member and at its opposite extremity in a head adapted to engage the web of a rail seating against said abutment. 40

In testimony whereof I affix my signature. 45
JOHN F. HAWLEY. [L.S.]
